CLAIM

The ornamental design for a workpiece clamp for flat bed jig, as shown and described.

DESCRIPTION

FIG. 1 is a front, right, top perspective view of a workpiece clamp for flat bed jig showing my new design; FIG. 2 is a front elevational view thereof, the rear elevational view being a substantially identical mirror image of FIG. 2;

FIG. 3 is a left side elevational view thereof;

FIG. 4 is a right side elevational view thereof;

FIG. 5 is a top plan view thereof; and

FIG. 6 is a bottom plan view thereof.
